UNITED STATES PATENT OFFICE

2,522,209

MAGNETICALLY CONTROLLED ELECTRIC
DISCHARGE DEVICEJames D. Cobine, Niskayuna, N. Y., assignor to
General Electric Company, a corporation of
New York

Application January 19, 1949, Serial No. 71,731

5 Claims. (Cl. 250—27.5)

1

My invention relates to electric discharge devices and more particularly to an electric discharge device of the gas filled type such as may be used to synchronize the operation of a plurality of electrical circuits, or to generate electrical oscillations or electrical noise.

It has for one of its objects the provision of an improved device of this character.

Another object is to provide an electric discharge device of the above type which is of relatively simple construction and yet effectively accomplishes the work usually done by a plurality of such devices.

In general, my invention comprises a gas filled thermionic electric discharge device having a centrally positioned cylindrical cathode, an ionization maintaining anode to establish suitable discharge conditions and a plurality of "signal" anodes concentrically displaced around the cathode. A substantially uniform magnetic field in a plane perpendicularly cutting the electrodes is rotated so that the magnetic flux passes through the cathode and each signal anode consecutively. Under proper operating conditions, the electrical potentials generated between the cathode and the particular signal anode whose connecting line is geometrically perpendicular to the direction of the magnetic field consist only of electrical noise; but the potentials generated between the cathode and signal anode combination parallel to the magnetic field direction consist of both electrical noise and strong electrical oscillations. As the magnetic field rotates, the above phenomena rotates with it and simultaneously causes an appreciable change in peak alternating voltage as it passes from one anode to the next.

The foregoing properties of my new electric discharge device can be used for many different applications in many different types of electrical circuits. In order to obtain secrecy of communication, for example, the noise voltage can be switched by the rotating magnetic field to a number of communication channels in sequence to provide alternating periods of speech and noise. The oscillating voltage can be used as a synchronized source of radio frequency, and the corresponding change of peak alternating voltage may be employed for switching or synchronizing purposes.

The novel features which I believe to be characteristic of my invention are set forth with particularity in the appended claims. My invention itself, however, together with further objects and advantages thereof may best be un-

2

derstood by reference to the following description taken in connection with the accompanying drawings, in which Fig. 1 is a side sectional view of an electric discharge device embodying my invention, Fig. 2 is a sectional view taken along line 2—2 of Fig. 1, Fig. 3 is a chart showing the change in the level of electrical noise and peak alternating voltage as a function of an increasing magnetic field, Fig. 4 is a chart showing the relative changes in the frequencies of oscillation and the amplitudes of these oscillations as a function of an increasing magnetic field, and Fig. 5 is a block diagram of a speech scrambling system embodying my invention.

15 Referring to the drawings, I have shown my invention in one form as comprising a substantially cylindrical closed tube or envelope 1, preferably glass, containing a gas such as argon or helium at non-critical pressure between 5 to 1000 microns. Argon at a pressure in the neighborhood of 100 microns, for example, is quite satisfactory.

20 A thermionic element, preferably of the indirectly heated type such as a cylindrical cathode 2, extends axially within tube 1 and is pressed, molded or otherwise secured to an insulated support 3 attached to a base 4. An ionization maintaining anode 5 operating with an electrical potential great enough to maintain a condition 25 of gas ionization within tube 1 is secured to an end of the tube 1 and preferably centered on the axis of the cathode. A suitable external lead 6 extends from anode 5 out through envelope 1.

25 A pair of auxiliary anodes, which may be in 30 the form of conductive rods or plates such as signal anodes 7 and 8, are radially displaced from cathode 2. These anodes 7 and 8 face the cathode and are preferably displaced 90° with respect to each other. Although I have shown only one 35 such pair of auxiliary anodes, it is obvious that a plurality of similar pairs of anodes may be arranged around cathode 2 in order to multiply the effect of a single pair. Although not illustrated in the drawings, suitable terminals for 40 cathode 2, anodes 7 and 8, and heater coil wires 45 9 and 10 are, of course, provided in base 4.

45 In order to create a substantially uniform 50 magnetic field across tube 1, I provide a permanent magnet 11 having poles 12 and 13 on either side of envelope 1 diametrically opposite cathode 2. When magnet 11 is rotated by any suitable 55 mechanical means (not shown), the magnetic field passes through anodes 7 and 8 consecutively. Although I have diagrammatically illustrated the magnetic field as created by a permanent

magnet 11 mechanically rotated, an alternative system of electromagnetic coils carrying suitably varying currents may, of course, be employed.

In typical circuit operation, the ionization maintaining anode potential with respect to the cathode is high enough to cause ionization of the gas, and the magnetic field is strong enough to suppress completely the oscillations in the particular anode-cathode combination perpendicular to the magnetic field. In a tube of conventional size, anode voltages between 100 to 1000 volts and a magnetic field intensity of between 20 to 100 gauss are quite satisfactory.

The potentials between the cathode-anode combination not directly affected by the magnetic field, i. e., the anode-cathode combination whose connecting line is in a plane parallel to the direction of the field, normally consist of a low frequency oscillation having a frequency below 300 kilocycles, and a high frequency oscillation having a frequency greater than 500 kilocycles, superimposed upon random electrical noise and upon possible harmonics of both oscillations. The oscillation of the lower frequency is apparently a function of the position of the electrodes, the magnitude of discharge current, and the type and pressure of the inserted gas. It is virtually independent of external circuit constants. These oscillations may be considered as a positive ion plasma oscillations whose energy is transmitted to the external circuit by velocity modulation of the electron beam passing directly from cathode to anode.

The electrical characteristics of an anode-cathode combination as a transverse magnetic field is introduced and increased due to the rotation of magnet 11 are plotted in Figs. 3 and 4 as a function of the magnetic field. It will be appreciated that although the curves shown in Figs. 3 and 4 are typical, they are only exemplary and for purposes of discussion. Considerable variation can be, of course, effected by tube design, gas pressure, operating potentials and other variables.

The low frequency oscillations shown in an exemplary curve F_1 of Fig. 3 do not change in frequency, but decrease in amplitude as illustrated by curve F_1' until they become merged in the noise level and completely lose their identity. This phenomenon may be considered as caused by the removal by the magnetic field of electrons that would otherwise reach the anode without collision with gas atoms from the current reaching the anode.

The higher frequency oscillations shown in auxiliary curve F_2 are less stable and increase in frequency as the magnetic field is introduced, but decrease in amplitude as illustrated by curve F_2' to finally also merge in the noise level under the influence of a sufficiently strong magnetic field. Referring to Fig. 4, the noise level illustrated by the curve so labelled first decreases and then slowly increases. The rotation of the magnetic field causes only a slight reduction of average current but an appreciable change in peak alternating voltage as shown by the curve bearing this legend.

Therefore, as the substantially uniform magnetic field is rotated from a parallel direction to a direction that is perpendicular with respect to a particular signal anode-cathode line, the following marked electrical changes occur: The characteristic oscillations are suppressed, the noise level is increased, and the peak alternating voltage resulting from both the oscillations and

the electrical noise is appreciably reduced. As the magnetic field continues to rotate back toward a direction parallel to the anode-cathode line, the oscillations return, the noise level is decreased, and the peak alternating voltage is increased to its original level.

Because of its unique electrical characteristics, my invention may be employed to fulfill many widely differing functions in electrical circuits. An appreciation of its versatility can be obtained by reference to Fig. 5 in which I have shown my invention as applied to a speech scrambling circuit for preserving secrecy of communication. A source of unidirectional electromotive force, such as battery 14, is connected through suitable impedance elements 15 to the ionization maintaining anode 5 to establish suitable discharge conditions and to the auxiliary anodes 7 and 8. The electrical noise generated at anodes 7 and 8 is applied through respective conventional noise amplifiers 16 and 17 to a pair of intelligence modulated radio frequency output channels A and B, respectively. These noise amplifiers preferably include an oscillation rejecting filter network such as a parallel tuned circuit to reject the radio frequency oscillations within tube 1.

When the direction of the magnetic field generated by magnet 11 is in a position parallel to the line connecting cathode 2 and anode 7, the peak noise voltage between these electrodes is at its minimum value, and the intelligence signal applied to channel A from a suitable modulation source 18 can be separated from the low level of random electrical noise reaching the channel A through the noise amplifier 16. As the magnetic field is rotated toward a direction perpendicular to the anode 7-cathode 2 line, the noise level increases until the signal voltage is merged in the noise voltage to become completely unintelligible. Simultaneously, the magnetic field is also approaching a direction parallel to the line connecting anode 8 and cathode 2, thereby decreasing the noise voltage which is being applied to communication channel B through noise amplifier 17. Therefore, as magnet 11 is rotated, the output of channel A consists of intelligence signal voltage alternating with noise, and the output of channel B has a similar pattern 180° out of phase with channel A. If both channels A and B are modulated by the same continuing signal from source 18, a proper receiving system can combine both channels, eliminate the noise by a synchronized switching circuit and receive only the intelligible signal. The rate of alternation of signal and noise is, of course, determined by the speed of rotation of magnet 11.

A modification of the foregoing speech scrambling system may obviously be made by using the oscillations generated at anodes 7 and 8 as a source of radio frequency for the communication channels as illustrated by the dashed lines of Fig. 5. These oscillations may be applied to the channels through conventional tuned amplifiers, blocks 19, 20, and are present during the interval on each channel that the intelligence signal is easily discernable over the noise voltage. Many other applications of my invention, such as the operation of relay circuits by the variation in the noise level or by the change in the peak alternating voltage as magnet 11 is rotated, will obviously occur to those skilled in the art.

While I have shown a particular embodiment of my invention, it is to be understood that I do not wish to be limited thereto since many modifications may be made, and I, therefore,

contemplate by the appended claims to cover any such modifications as fall within the true spirit and scope of my invention.

What I claim as new and desire to secure by Letters Patent of the United States is:

1. An electric discharge device comprising a sealed envelope containing a gaseous medium and enclosing a longitudinally extending cathode, a plurality of signal anodes located in spaced relation around said cathode and an ionization maintaining anode spaced from said cathode and said signal anodes, input connections to said cathode and said ionization maintaining anode for supplying voltage therebetween to ionize said gaseous medium, and a rotating magnetic field producing means surrounding said envelope for providing a substantially uniform transverse magnetic field which rotates around said cathode through each signal anode consecutively to vary the electrical characteristics of said ionized gaseous medium between said cathode and said signal anodes.

2. An electric discharge device comprising a gas filled hermetically sealed envelope containing a thermionic cathode extending along the longitudinal axis thereof, at least one pair of signal anodes circumferentially spaced around said cathode and an ionization maintaining anode axially spaced from said cathode, electric connecting means for supplying voltage to said electrodes to ionize the region between said cathode and said signal anodes, and a magnetic system external said envelope in a plane which cuts said cathode and said signal anodes for producing a rotating substantially uniform magnetic field which diametrically traverses said envelope through said cathode and passes through each signal anode consecutively during its rotation to vary the electrical characteristics of said ionized region.

3. An electric discharge device comprising a sealed envelope containing an inert gaseous medium, a cylindrical thermionic cathode extending within said envelope along the longitudinal axis thereof, a pair of signal anodes located at 90 degree circumferentially spaced points around said cathode within said envelope, an ionization maintaining anode centered on said longitudinal axis within said envelope in axial spaced relation to said cathode, independent input connections to said cathode, said signal anodes and said ionization maintaining anode for supplying voltage thereto to ionize the region between said cathode and said signal anodes and means including a magnetic system having poles on diametrically opposite sides of said envelope in a plane which traverses said cathode and said signal anodes for producing a rotating magnetic field which revolves around said cathode through

each signal anode consecutively to vary the electrical characteristics of said ionized region.

4. An electric discharge device comprising an envelope containing a gaseous medium and enclosing a centrally positioned thermionic cathode, at least one pair of signal anodes circumferentially spaced 90 degrees around said cathode and an ionization maintaining anode spaced from said cathode and said signal anodes, independent input terminal connections to said cathode, said signal anodes and said ionization maintaining anode for supplying voltage thereto to ionize said gaseous medium and establish electrical oscillations between said cathode and said signal anodes, and a magnetic system having poles on diametrically opposite sides of said envelope for producing a rotating magnetic field which revolves around said cathode through each signal anode consecutively thereby to suppress said oscillations intermittently.

5. An electric discharge device comprising an envelope containing a gaseous medium and enclosing an axially extending thermionic cathode, at least two signal anodes circumferentially spaced around said cathode and an ionization maintaining anode axially spaced from said cathode and said signal anodes, input terminal connections to said cathode and said ionization maintaining anode for supplying voltage therebetween to ionize said gaseous medium and to produce a noise voltage between said cathode and said signal anodes, and means for varying the level of said noise voltage comprising a magnetic system having poles on diametrically opposite sides of said envelope for producing a rotating magnetic field which revolves around said cathode through each signal anode consecutively.

Certificate of Correction

Patent No. 2,522,209

September 12, 1950

JAMES D. COBINE

It is hereby certified that error appears in the printed specification of the above numbered patent requiring correction as follows:

Column 3, line 13, for "100 gauss" read *1000 gauss*;
and that the said Letters Patent should be read as corrected above, so that the same may conform to the record of the case in the Patent Office.

Signed and sealed this 9th day of January, A. D. 1951.

[SEAL]

THOMAS F. MURPHY,
Assistant Commissioner of Patents.
